UNITED STATES PATENT OFFICE.

ALBERT H. STEBBINS, OF LOS ANGELES, CALIFORNIA.

OPERATING MEANS.

Application filed October 8, 1924. Serial No. 742,386.

To all whom it may concern:

Be it known that I, ALBERT H. STEBBINS, a citizen of the United States, residing at Los Angeles, in the county of Los Angeles and State of California, have invented an Improvement in Operating Means, of which the following description, in connection with the accompanying drawings, is a specification, like characters on the drawings representing like parts.

This invention relates to vibrating means for operating screens and table concentrators.

Screens are employed to separate materials in accordance with the differences in size, and table concentrators are employed to separate materials in accordance with the differences in specific gravity. In both screens and table concentrators the material supporting surface is usually mounted for a vibratory movement, and the nature of the movement employed in both types of machines is important.

In screens the movement employed may serve to promote travel of the materials lengthwise of the screen, to shift the materials so that they are presented to the screen surface for thorough treatment, and also to shake the screen in a manner to dislodge particles from the apertures of the screen, or if desired the movement employed may serve only one or more of these purposes.

In table concentrators the movement employed commonly serves to promote travel of the materials lengthwise of the deck and also to promote stratification, and in accomplishing these results the deck must not be vibrated with sufficient force to disturb the different strata into which the materials are being formed.

One of the best known movements for advancing materials along the surface of a screen or deck comprises a back and forth movement which reverses its direction slowly at one end of its path of travel and quickly at the other end of the path of travel. This constitutes a progressive movement that causes the materials to slide a short distance lengthwise of the deck each time the movement is checked suddenly at one end of the path of travel.

The vibrating means of the present invention may be employed to impart various different movements to a material supporting surface, and is therefore well adapted to operated screens, concentrator decks and other forms of separators.

One important feature of the present invention resides in a pair of operating eccentrics which are disposed at an angle to each other so that each serves to modify the action of the other upon the supporting surface being vibrated.

It is well known that when an eccentric is employed to produce a reciprocatory movement, the speed of movement is relatively slow at each end of its stroke and is greatest at a point about halfway between the ends of the stroke. By employing two eccentrics, in accordance with the present invention, one eccentric may serve to reverse the movement of the object being operated at the instant it is traveling at its greatest speed under the control of the other eccentric. In this manner an ideal progressive movement is obtained as the travel of the material supporting surface in one direction may be reversed as quickly as desired, and by changing the relative angle of the two eccentrics the movement may be varied as desired.

Another feature of the invention resides in eccentrics which are operated to exert a force upon first one side of a material treating frame and then the other so that the eccentrics will impart a combined back and forth and side twitch movement to the frame. This movement is particularly well adapted to operate screens as it will dislodge particles from the apertures of the screen surface.

Still another feature of the invention resides in three or more eccentrics disposed side by side at an angle to each other in such a manner that each modifies the action of the others upon the material supporting surface being vibrated.

Other features of the invention and novel combination of parts in addition to the above will be hereinafter described in connection with the accompanying drawings which illustrate good practical forms thereof.

In the drawings:—

Fig. 1 is a top plan view of a screen pro-

vided with the vibrating mechanism of the present invention.

Fig. 2 is a side view of Fig. 1.

Fig. 3 is a sectional view taken on the line 5 3—3 of Fig. 2.

Fig. 4 is a sectional view taken on the line 4—4 of Fig. 2.

Fig. 5 is a transverse sectional view of a modification of the invention.

10 Fig. 6 is a sectional view through the operating shaft and taken on the line 6—6 of Fig. 1.

Fig. 7 is a sectional view taken on the line 7—7 of Fig. 8.

15 Fig. 8 is a face view of an operating shaft provided with three eccentrics.

Figs. 9, 10 and 11 are diagrammatic views illustrating the action of two eccentrics when they are disposed at an angle of 180 degrees 20 to each other.

Figs. 12, 13 and 14 are diagrammatic views illustrating the action of two eccentrics disposed at an acute angle to each other; and

25 Figs. 15, 16 and 17 are diagrammatic views illustrating the action of three angularly disposed eccentrics.

The vibratory mechanism of the present invention is shown in connection with a screen, as it is admirably adapted to operate 30 a screen with a back and forth movement and also a side twitch movement, but since any desired movement may be obtained in accordance with the present invention by changing the relative angle of the operating 35 eccentrics, the present invention may also be employed to vibrate the deck of a concentrator table or operate other forms of separators employing a vibratory movement.

In the embodiment of the invention shown, 40 a supporting base is provided consisting of spaced, longitudinally extending beams 10 that may be secured in spaced relation by any suitable means, not shown. Upon the base 10 is mounted the screen frame consisting of longitudinally extending side walls 11 connected by end walls 12. The materials to be treated are delivered to the screen by a hopper 13 secured to one end of the screen frame, and the screen frame is shown as 45 provided with an upper screening surface 14 and a lower screening surface 15. These screening surfaces may be secured in a stretched condition to the opposite sides of the frame in any well known manner.

50 As above stated the operating means of the present invention serves not only to move the material supporting surface back and forth, but may also impart a side twitch movement to the surface which will serve to dislodge particles from the apertures therein. In 55 order to impart both movements to the screen frame it is necessary that the frame be supported so that it may move freely in various directions, and to this end in the present case the screen frame is shown as

supported by coiled springs 16, the lower ends of which rest upon the beams 10 and the upper ends of which rest against and are secured to the under face of the transversely extending braces 17, which braces are secured to the screen frame. Four of the supporting springs 16 are shown in the drawings, but it is apparent that any desired number may be employed. These supporting springs permit the frame not only to be 70 moved back and forth and transversely, but also in a vertical direction to a limited degree, by compressing the springs and then allowing them to expand.

In the construction shown in Figs. 1 to 4 inclusive, the screen frame is operated from a main shaft 18 which is journaled in bearings 19 secured to the beams 10 and this shaft may be rotated by the pulley 20 secured to an end thereof. The shaft 18 is 80 provided with a pair of angularly disposed eccentrics 21 and 22 at one side of the screen and a second pair of angularly disposed eccentrics 23 and 24 at the opposite side of the screen. Various means might be provided 85 for imparting movement from the eccentrics to the screen frame and in the construction shown this is accomplished by providing a pivoted lever 25 which is operated by one pair of eccentrics and a second pivoted lever 26 which is operated by the other pair of eccentrics. The levers 25 and 26 are secured to the transversely extending shaft 27, which is supported by brackets 27^a and the shaft 90 may be rotatably mounted in these brackets or, if preferred, the levers 25 and 26 may be 95 rockingly mounted on the shaft 27. Each lever has a relatively wide face adapted to extend over both eccentrics of a pair so that either eccentric may impart a rocking movement to the lever. The eccentrics in the construction shown do not directly engage the levers 25 and 26, since considerable friction would be produced if the eccentrics rotated 100 against the face of the lever, and to prevent this loss of energy and wear each eccentric is provided with an outer ring 28 (see Fig. 6) which surrounds the eccentric proper and is supported upon the eccentric by anti-friction bearings 28^a of any well known or 105 preferred construction. As a result of this construction each eccentric rotates freely within its outer ring, and the rings are moved by the eccentrics into and out of operative engagement with the rocking levers 25 and 26 to operate the levers without rotating 110 relatively thereto.

In the present construction movement is imparted to the screen frame from the levers 25 and 26 by cables 29 and 30 actuated by 125 the respective levers. Each cable has one end securely fastened to a rocking lever as at 31, and an intermediate portion of each cable extends lengthwise of the screen frame and 130 is rigidly secured thereto. In the construc-

tion shown, each cable is secured to a side of the frame at three points by clamps 32 and each cable is further supported by grooved blocks 33 secured to the side of the frame 5 and which support the cable when it is pulled downwardly at a slight angle, as shown in Fig. 2. In the construction shown the operating levers 25 and 26 are disposed near the hopper end of the screen, and adjacent the opposite end of the screen is mounted a transversely extending shaft 34 supported by brackets 35 that are fastened to the beams 10 and upon the shaft 34 are rotatably mounted the idle sheaves 36. One 10 end of each cable 29 and 30 extends from the screen frame about a grooved sheave 36 and the end of the cable is yieldingly secured to a beam 10. In the construction shown the yielding anchor for each cable consists of a 15 relatively long threaded bolt 37 having a cable receiving hook at one end. Each bolt 37 is slidably mounted in a bracket 38 secured to a beam 10 and a coiled spring 39 is confined between one face of the bracket 38 and a cup 40 mounted upon the bolt 37 and held in place by adjustable nuts 41. The arrangement is such that the tension of each 20 spring 39 may be varied as desired by adjusting the nuts 41.

From the above description, when read in connection with the drawings, it will be seen that when a lever 25 is rocked upwardly by either of its eccentrics the cable will be pulled in a left-hand direction, viewing 25 Fig. 2. This will pull the side of the screen frame to which the cable is secured in a left-hand direction and will compress the cable anchoring spring 39, and when the eccentrics permit the operating lever to rock 30 in a clockwise direction, the screen frame will move in a right-hand direction under the action of the compressed spring 39.

As stated, it is desirable to impart a side twitch movement to the screen frame, in 35 addition to the back and forth movement in the direction of its length, and this is accomplished by securing the eccentrics 21 and 22 to their operating shaft out of alignment with the eccentrics 23 and 24, the arrangement of the eccentrics being such that first one rocking lever and then the other is actuated so that one side of the screen frame is pulled and then the other. This 40 will impart a side twitch movement to the screen frame, as indicated by dotted lines in Fig. 1. The nature of the movement imparted to the screen frame may be varied as desired by changing the angular position of the various eccentrics and if it is 45 desirable to dispense with the side twitch movement just mentioned, this may be accomplished by placing the pair of eccentrics at one side of the screen frame in angular alignment with the eccentrics at the opposite side of the frame.

Various means other than the rocking levers 25 and 26 may be employed for imparting movement from the eccentrics 21, 22, 23 and 24 to the screen frame, but the construction shown is desirable because it 50 permits a single cable to be operated from a pair of eccentrics.

If a progressive movement is to be imparted to a screen to advance the materials lengthwise thereof, it is necessary to arrest 55 the movement of the material operating surface more promptly in one direction than the other. As above stated, the use of a pair of angularly disposed eccentrics, in accordance with the present invention, is admirably adapted to produce the desired progressive movement. The eccentrics may be disposed at various angles to each other and in Figs. 6 and 9 the eccentrics are indicated as disposed at an angle of 180 degrees to 60 each other. The nature of the movement obtained by a pair of eccentrics positioned as shown in Figs. 6 and 9 may be understood by studying Figs. 9, 10 and 11, wherein the vertical line 42 indicates the face of 65 a lever such as 25, resting against one or both of the eccentrics 21 and 22. The point a of Fig. 9 indicates the shortest radius or the position of the lever 42 when it lies nearest to the operating shaft 18. As the shaft 70 and eccentrics rotate in the direction indicated by the arrow in Fig. 9, the lever 42 will move outwardly to the successive positions indicated in Fig. 10 by the length of the lines a, b, c and d, d being the maximum movement imparted to the lever 42, and as the eccentric 22 continues to rotate, the lever 42 will approach the main shaft 18 as the points e, f and g successively engage 75 the lever 42. It will be understood that the lever 42 is moving towards the shaft 18 at its maximum speed, as the eccentric rotates to bring the points f and g successively into engagement with the lever 42, but at the instant the point g engages the lever, the movement of the lever in a left-hand direction is checked by the second eccentric 21 moving into engagement with the same, and, under the influence of this second eccentric, the lever 42 is rapidly moved in a right-hand direction; by thus rapidly reversing 80 the direction of movement of the lever 42, the desired progressive movement is imparted to the materials supported by the screen. The nature of the movement produced by each of the eccentrics 21 and 22, when they are disposed 180 degrees apart is indicated by the curves plotted in Fig. 85 11. In Figs. 12, 13 and 14, the eccentrics are indicated as disposed at an angle of 90 degrees to each other. Upon examining the diagram shown in Fig. 14, it will be seen that the angular disposition of eccentrics shown in Fig. 12 serves to produce a momentary change in the direction of the 95

movement of the lever 42, as the points *f*, *g* and *h* pass successively into engagement with the lever 42. This is due to the fact that the radius *g* is slightly shorter than the maximum radii *f* and *h* of the two eccentric.

It may be desirable to avoid the slight dip indicated at the point *g* in the diagram of Fig. 14 and to make the reversal of the direction of movement of the screen frame at one end of its path of travel more gradual than may be obtained by a pair of eccentrics. In this case three angularly disposed eccentrics 43, 44 and 45 may be employed, as indicated in Figs. 7 and 8; and these three eccentrics may act against the face of a single lever 46. The nature of the movement imparted to a lever by these three eccentrics may be observed by examining Figs. 15, 16 and 17. In Fig. 17, it will be seen that the upper portion of the curve of the diagram is nearly a straight line, thus indicating a reversal of movement which is more gradual than that obtained in either Fig. 11 or 14.

In some cases it may be desirable to impart a pronounced side twitch movement to a screen frame, without employing also a substantial progressive movement, in which case the pair of eccentrics provided near each end of the main shaft 18 may be replaced by a single eccentric 47, provided at the left hand side of the screen and a single eccentric 48 at the right hand side of the screen as shown in Fig. 5, and one of these eccentrics may operate against the lever 25 while the other operates against the lever 26. The eccentrics 47 and 48, it will be understood, are disposed at an angle of 180 degrees, or any other desired angle to each other, so that they will exert a pull upon first one side of the screen frame and then the other, to move it back and forth with a pronounced side twitch movement.

What is claimed is:

1. In a device of the class described, the combination of a supporting base, a frame supported by the base for vibratory movement, means for moving the frame in one direction, means for moving the frame in the opposite direction, including levers pivotally secured to the base at each side thereof, cables operatively connecting each lever to a side of the frame, and a pair of angularly disposed eccentrics for rocking one lever and a second pair of angularly disposed eccentrics for rocking the other lever.

2. In a device of the class described, the combination of a supporting base, a frame supported by the base for vibratory movement, means for moving the frame in one direction, means for moving the frame in the opposite direction, including levers pivotally secured to the base at each side thereof, a connection between each lever and the

adjacent side of said frame, and a pair of angularly disposed eccentrics for rocking one lever and a second pair of angularly disposed eccentrics for rocking the other lever.

3. In a device of the class described, the combination of a supporting base, a frame supported by the base for vibratory movement, means for moving the frame in one direction, means for moving the frame in the opposite direction, including rocking levers pivotally mounted at the opposite sides of the base and each lever having an enlarged portion near the lever pivot provided with a curved cable receiving surface, cables for operatively connecting each lever to a side of the frame, and eccentrics for rocking the levers in a direction to pull the cables and vibrate the frame.

4. In a device of the class described, the combination of a supporting base, a frame supported by the base for movement both longitudinally and transversely, yielding means for moving the frame in one direction, means for moving the frame in the opposite direction and for imparting a side twitch movement to the frame, including a pair of eccentrics located at the opposite sides of the frame, and cables for imparting the movement of one eccentric to one side of the frame and the movement of the other eccentric to the other side of the frame, said eccentrics being angularly disposed so that they pull first one side of the frame and then the other.

5. In a device of the class described, the combination of a supporting base, a frame supported by the base for movement both longitudinally and transversely, operating cables secured to the opposite sides of the frame to provide a flexible connection between the frame and each actuating means, spring means acting upon the cables to pull the frame in one direction, eccentrics disposed at the opposite sides of said frame and operable upon the cables to pull the frame in the opposite direction and to control the movement of the frame under the action of said spring means.

6. In a device of the class described, the combination of a supporting base, a frame supported by the base for vibratory movement in the direction of its length, means for moving the frame in one direction, means for moving the frame in the opposite direction including a pair of angularly disposed eccentrics adjacent one side of the frame, a second pair of angularly disposed eccentrics adjacent the other side of the frame, and means for imparting movement from each pair of eccentrics to the respective sides of the frame.

7. In a device of the class described the combination of a supporting base, a frame supported by the base for movement both longitudinally and transversely, means for

- moving the frame in one direction, means for moving the frame in the opposite direction and for imparting a side twitch movement to the frame including a pair of angularly disposed eccentrics adjacent one side of the frame, a second pair of angularly disposed eccentrics adjacent the other side of the frame and out of angular alignment with the first pair of eccentrics, and means for imparting movement from each pair of eccentrics to one side of the frame and from the other pair of eccentrics to the opposite side of the frame to vibrate the same with a side twitch movement.
15. 8. In a device of the class described, the combination of a supporting base, a frame supported by the base for vibratory movement in the direction of its length, means for moving the frame in one direction, means for moving the frame in the opposite direction, including levers pivotally secured to the base at each side thereof, a pair of cables for operatively connecting the sides of the frame to the respective levers, and a pair of eccentrics, one for operating each lever, to actuate the frame.
9. In a device of the class described, the combination of a supporting base, a frame supported by the base for movement both longitudinally and transversely, means for moving the frame in one direction, means for moving the frame in the opposite direction and for imparting a side twitch movement to the frame, including levers pivotally secured to the base at each side thereof, a pair of cables for operatively connecting the sides of the frame to the respective levers, and a pair of eccentrics one for operating each lever and angularly disposed so that they pull first one side of the frame and then the other.
10. In a device of the class described, the combination of a supporting base, a frame supported by the base for vibratory movement, means for moving the frame in one direction, three angularly disposed eccentrics for moving the frame in the opposite direction and for controlling the movement of the frame under the action of said means, and means actuated by a partial rotation of each eccentric for operating the frame.
11. In a device of the class described, the combination of a supporting base, a frame supported by the base for vibratory movement, means for moving the frame in one direction, three angularly disposed eccentrics for moving the frame in the opposite direction and for controlling the movement of the frame under the action of said means, a lever actuated by the partial rotation of each eccentric, and means for operatively connecting the lever to the frame to actuate the latter.
12. In a device of the class described, the combination of a supporting base, a frame supported by the base for vibratory movement, means for moving the frame in one direction, a rotating shaft, three eccentrics secured to said shaft in different angular relation, and means actuated by the three eccentrics to move the frame in the opposite direction and to control its movement so that it will reverse slowly at one end of its path of travel and quickly at the other end of its path of travel.
13. A separator for treating materials comprising, in combination, a supporting base, a frame supported by the base for free movement both longitudinally and transversely, cables connected to the opposite sides of the frame to pull the frame in the direction of its length and arranged so that they will not interfere with the lateral movement of the frame, angularly disposed eccentrics operable to pull first one cable and then the other to vibrate the frame with a side twitch movement, and spring means for yieldingly forcing the frame in the cable tightening direction.

In testimony whereof, I have signed my name to this specification.

ALBERT H. STEBBINS.
